(57) **CLAIM**

I claim, the ornamental design for a MP3 loading apparatus, as shown and described.

DESCRIPTION

FIG. 1 is a front elevational view of the MP3 loading apparatus showing my new design;

FIG. 2 is a top plan view of the MP3 loading apparatus thereof;

FIG. 3 is a bottom plan view of the MP3 loading apparatus thereof; and,

FIG. 4 is a perspective view of the MP3 loading apparatus thereof.

1 Claim, 4 Drawing Sheets

FIG. 1

FIG. 2

FIG. 3

FIG. 4
